PROTECTIVE DEVICE FOR LATCH-CONDITIONING ELEMENTS Earl M. Trammell, Jr., Gatesworth Apt., 245 Union Blvd.,
St. Louis, Mo.

Filed Sept. 10, 1956, Ser. No. 608,926

5 Claims. (Cl. 70—181)

This invention relates generally to protective devices for latch-conditioning elements, and more particularly to devices of this character used on automobile doors to control selectively the operation of latch-conditioning elements.

The present developments constitute certain improvements over the subject matter of patent No. 2,708,845 issued May 24, 1955 to this applicant, and entitled Lock-Plunger Guarding Devices.

Many automotive vehicles are equipped with a reciprocating plunger on each door operable through an aperture in the door frame, the plunger serving to condition the latch mechanism of the door through a plunger rod to prevent operation from inside or outside the door. Accidents are frequently reported involving children and sometimes others, who unintentionally actuate the inside door latch, permitting opening of the car door and injury of the occupants through falling from a moving vehicle. One of the principal objectives of the present invention is to obviate such hazards.

An important object is realized by a protective device that prevents the unintended, casual or otherwise unwanted manipulation of door latch-conditioning elements from door-locking position to door-unlocking position.

Still another important objective is achieved by a protective arrangement of the type described that affords the advantages discussed above, yet enables completely normal and conventional use of the plunger for latch-conditioning purposes when such is desired.

Yet another important objective is realized by the provision of a protective device which utilizes a slide element that is completely shielded to preclude digital actuation, yet adapted to be actuated by an instrument such as a key so that the element selectively prevents unwanted movement of the plunger head in one direction of its range of travel.

Other important advantages are achieved by the provision of means that indicate visually that a movable lock element is positively engaging the plunger head to prevent direct digital operation of the plunger head, as for example from the door-locking position to the door-unlocking position, thus indicating a safe condition for the occupants of the automobile. In addition, such means indicate visually when the lock element is operatively disconnected from the plunger head to permit normal plunger head operation, thus indicating a condition in which the plunger head may be unintentionally moved to a door-unlocking position.

Another important objective is realized by the structural arrangement and functional cooperation of the plunger head with the movable safety lock element which enables positive engagement when the plunger head is disposed in one limit of its range of travel to preclude movement to the other limit.

Other important advantages are realized in that the protective devices are simple and durable in construction, economical to manufacture and easy to assembly. Such devices may be readily utilized by any person with the

2

proper actuating instrument without requiring any special skill or any complicated instructions.

The foregoing and numerous other objects and advantages of the invention will more clearly appear from the following detailed description of two embodiments, particularly when considered in connection with the accompanying drawings, in which:

Fig. 1 is a top plan view of the protective device for a latch-conditioning element mounted on a frame element of an automobile door;

Fig. 2 is a fragmentary, cross sectional view as seen along line 2—2 of Fig. 1;

Fig. 3 is a view partly in cross section as seen along line 3—3 of Fig. 2, and

Fig. 4 is a fragmentary cross sectional view as seen along line 4—4 of Fig. 2;

Fig. 5 is a top plan view of a modified protective device for a latching mechanism;

Fig. 6 is a fragmentary view, partly in cross section, as seen along line 6—6 of Fig. 5, and

Fig. 7 is a view partly in cross section as seen along staggered line 7—7 of Fig. 6.

Referring now by characters of reference to the drawings, it will be particularly noted that the protective devices are disclosed as being utilized on an automobile door that includes inside glass frame 10, outside glass frame 11 and window glass 12.

As is conventional in most present day automobiles, a plunger assembly generally indicated at 13 (Fig. 2) is used to condition the latch mechanism of the door against operation from inside or outside the door. The plunger assembly 13 includes a plunger head 14 attached to the top of a plunger rod 15 that is connected to the door latch through suitable mechanism not shown. The plunger head 14 is disposed and mounted so that it is reciprocally movable through an aperture 16 formed in the inside glass frame 10. A rubber grommet 17 is attached to the margins defining aperture 16, the grommet 17 serving to provide a close fit with plunger head 14 and to protect the plunger head from engagement with the metal glass frame 10.

The plunger head 14 includes a reduced shank portion 20 and a subjacent, enlarged portion 21 to provide a lock shoulder 22, the purpose of which will more clearly appear from the subsequent description of the other parts of the protective device.

Located in a rectangular opening 23 formed in glass frame 10 immediately adjacent the plunger assembly 13, is a housing guard structure generally referred to at 24 in Figs. 1—4. The guard structure 24 includes outwardly flared, integral marginal flanges 25 that seat on the top of glass frame 10 along the marginal portions defining rectangular opening 23. A plurality of screws 26 secure guard structure 24 to glass frame 10, the screws 26 preferably extending upwardly through glass frame 10 into flanges 25 so that such screws are hidden from view. The top of flanges 25 are rounded so as to blend symmetrically with the outline of glass frame 10 and to present a smooth even surface.

The guard structure 24 includes side walls 27 that are integral with flared flanges 25 to provide an upwardly opened cup-like formation 30. Extending between side walls 27 and constituting the bottom of cup-like formation 30 is a shield element 31. The side walls 27 extend below shield element 31 and are provided with opposed, inturned lateral margins 32 that realize a socket formation 33 below shield element 31. It will be seen from Fig. 2 that the socket formation 33 is closed at the left end and at each side, and is open at the right end and along the bottom between inturned margins 32.

Slidably mounted in socket formation 33 is a slide element 34 constituting a safety lock element. The slide

element 34 is capable of being actuated in a manner and by a means subsequently described so that the end extending out of socket formation 33 moves into and out of the path of plunger head travel. This end of slide element 34 is provided with a recessed portion 35 that conforms substantially to the configuration of the reduced shank portion 20 of plunger head 14 immediately above shoulder 22, the recessed portion 35 providing spaced arms 36 adapted to embrace the reduced shank portion 20 as is more clearly shown in Figs. 2 and 3.

A slot 38 is formed in slide element 34, the slot 38 being partially defined by end margins 37 (Fig. 3) that constitute opposed spaced abutments. The spacing between margins 37 is sufficient to receive an actuating instrument such as a key. Formed in shield element 31 immediately above slot 38 is a cooperating elongate slot 40 of reduced size so as to preclude digital actuation of slide element 34 by access through slot 40, and yet of a size to permit access to abutment margins 37 by an actuating instrument such as a key. The slot 40 is of sufficient length so that the actuating instrument in engaging the abutment margins 37 may move the slide element 34 into and out of effective operative engagement with plunger head 14.

It will be particularly noted that slide element 34 is completely protected by shield element 31, and that the end portion extending out of socket formation 33 is located underneath glass frame 10 so that the slide element 34 cannot be actuated by direct digital manipulation, but only actuated by the use of a proper actuation instrument extended through shield slot 40 into engagement with abutment margins 37.

The protective device is provided with means for visually indicating whether or not slide element 34 is extended into operative engagement with plunger head 14 to prevent the plunger head from being directly actuated from the door-locking position to the door-unlocking position. This indicating means consists of a small opening 41 in shield element 31 and the provision of cooperating patches 39 and 42 of different colors on slide element 34 immediately underlying shield element 31. Of course, the opening 41 is small enough to preclude any digital manipulation of slide element 34 through such opening.

When slide element 34 is in its extended position to effectively lock plunger head 14, the green patch 39 is visible through opening 41, this meaning that the protective device is in safety operation. When slide element 34 is in the retracted position out of effective engagement with plunger head 14, the red patch 42 is located below and visible through opening 41, thus indicating that the plunger head 14 is capable of being directly actuated to a door-unlocking position, and thus indicating the existence of a hazard that the door may be unintentionally opened while the automobile is in motion.

It is thought that the operation and functional advantages of this protective device have become fully apparent from the foregoing detailed description of parts, but for completeness of disclosure it will be noted that when slide element 34 is in its retracted position relative to socket formation 33, the plunger head 14 is free to move reciprocally in the conventional manner through aperture 16 to condition the latch mechanism of the door.

When it is desired to prevent unintended or unwanted actuation of the plunger head 14 to the door-unlocking position, such always being the case when children occupy the rear seat compartment of a four-door automobile, the plunger head 14 is first moved downwardly to the door-locking position shown in Fig. 2, and then an actuating instrument such as a key is inserted through slot 40 into engagement with abutment margin 37, and the slide element 34 moved or extended by such instrument into the path of plunger head travel. In this extended position, the recessed portion 35 embraces the reduced shank portion 20 and arms 36 engage shoulder 22 to prevent movement of plunger head 14 to the door-unlocking position.

The green patch 39 is visible through opening 41 and indicates a safe condition.

In order to release plunger head 14, the actuating instrument must be inserted through slot 40 into engagement with abutment margin 37 to move slide element 34 back to its retracted position within socket formation 33, and hence move slide element 34 operatively out of the path of plunger head travel. With slide element 34 in its retracted position, the red patch 42 is visible through opening 41 and indicates that a door opening hazard does exist. The plunger head 14 is now capable of the usual manual manipulation.

It will be noted that slide element 34 cannot be extended effectively into the path of plunger head travel when plunger head 14 is in its door-unlocking position. For example, if slide element 34 were attempted to be moved by an actuating instrument operating through slot 40 and in engagement with abutment margin 37 into the path of plunger head travel when the plunger head 14 is in its door-unlocking position, the end of the slide element would merely abut the enlarged shank portion 21 and would not realize any effective engagement to prevent direct digital manipulation of plunger head 14. The protective device is only operable when plunger head 14 is in the door-locking position.

Figs. 5-7 inclusive disclose a modified protective device for a door latching mechanism. It will be apparent that the door frame includes corresponding elements disclosed in Fig. 1, that is, an outside glass frame 11, inside glass frame 10 and intervening glass 12. Moreover, the plunger assembly 13 is identical in construction with that previously described. Briefly, the plunger assembly 13 includes a plunger head 14 mounted on plunger rod 15, the plunger head 14 including reduced shank portion 20 and enlarged shank portion 21 that form lock abutment 22. The plunger head 14 is movable reciprocally through an aperture formed in inside glass frame 10, such aperture being defined by rubber grommet 17.

The protective device includes a safety lock element generally indicated at 45 consisting of a cylindrical head portion 46 and an elongate shank portion 47. The head portion 46 includes a flat upper surface having an integral peripheral flange 48 slidably mounted in a groove formed in ring mounting 50, the ring mounting 50 being secured to inside glass frame 10 in close proximity to the plunger assembly 13. Formed in head portion 46 is a narrow slot 51 adapted to receive an actuating instrument such as a key, the slot 51 being of reduced size to preclude direct digital actuation of safety lock element 45.

Shank portion 47 is formed integral with the lower portion of head portion 46 and is provided at the free end with a recessed formation 52 adapted to embrace the reduced plunger shank portion 20 immediately above lock shoulder 22 when the plunger head is disposed in the door locking position, as is illustrated in Figs. 6 and 7.

Upon rotation of head portion 46 by actuation of a key in slot 51, the shank portion 47 is swingably movable into and out of the path of plunger head travel. The shank portion 47 engages lock shoulder 22 to prevent movement of the plunger head to the door-unlocking position under the above described conditions. The shank portion 47 extends underneath the glass frame 10 and is completely protected from direct digital actuation.

Assuming that it is desirable to utilize the protective device, the plunger head 14 is first moved to the door-locking position. Then, an actuating instrument such as a key is inserted into narrow slot 51 and the locking element 45 is rotated in mounting structure 50 so that the recessed formation 52 embraces the reduced plunger shank portion 20 immediately above lock abutment 22, as is best shown in Figs. 6 and 7. In this position, the

lock element 45 prevents any digital actuation of the plunger head 14 from the door-locking position.

When it is desired to unlock the door, the actuating instrument is again inserted in narrow slot 51 and the lock element 45 is rotated out of the path of movement of the plunger head to the position shown in dotted lines in Fig. 5. With the lock element 45 disposed in this inoperative position, the plunger head 14 may be directly digitally manipulated to the door-unlocking position which is indicated in dotted lines in Fig. 6. The plunger assembly may now be operated in the conventional manner until it is again desired to utilize the protective device.

Although the invention has been described by making detailed reference to two embodiments, such detail is to be understood in an instructive, rather than in any restrictive sense, many variants being possible within the scope of the claims hereunto appended.

I claim as my invention:

1. In a device for selectively precluding actuation of a doortract-conditioning plunger, the device comprised of a plunger head movable within limits to condition the latch mechanism of the door, a slide element mounted for movement into and out of the path of plunger head travel, a housing structure about said slide element to prevent direct digital actuation thereof, the slide element being provided with abutment means, the housing structure being provided with an aperture immediately overlying and aligned with said abutment means through which an actuating instrument such as a key may be inserted for access to said abutment means for slide element actuation, the slide element selectively engaging the plunger head when the plunger head is disposed in one limit of its range of movement to preclude direct actuation.

2. In a device for selective precluding actuation of a doortract-conditioning plunger, the device comprised of a plunger head movable within limits to condition the latch mechanism of the door, a shield element on the door adjacent the plunger head, a slide element disposed underneath said shield element to prevent digital actuation of said slide element, means slidably mounting said slide element for movement into and out of the path of plunger head travel, the slide element being provided with an opening partially defined by opposed abutments, the shield element being provided with an aperture immediately overlying and aligned with said opening through which an actuating instrument such as a key may be inserted for access to said abutments for slide element actuation, the aperture being of reduced size to preclude digital actuation of the slide element by access through said aperture, the slide element selectively engaging the plunger head when the plunger head is disposed in one limit of its range of movement to preclude direct actuation to the other limit.

3. In a device for selectively precluding actuation of a doortract-conditioning plunger, the device comprised of a plunger head movable within limits through an aperture in a frame element of the door to condition the latch mechanism of the door, a slide element mounted adjacent said plunger head for movement into and out of the path of plunger head travel, the slide element being provided with spaced abutments, a shield structure located over said slide element to prevent digital actuation of said slide element, the shield structure being provided with an aperture immediately overlying and aligned with said abutments through which an actuating instru-

ment such as a key may be inserted for access to said abutments of the slide element for slide element actuation, the slide element being selectively movable into the path of plunger head travel when the plunger head is disposed in one limit of its range of movement to preclude direct actuation to the other limit.

4. In a device for selectively precluding actuation of a doortract-conditioning plunger, the device comprised of a plunger head movable within limits to condition the latch mechanism of the door, a housing guard structure located adjacent the plunger head, the guard structure including a socket formation and an overlying shield element, a slide element slidably mounted in said socket formation for movement into and out of the path of plunger head travel, the slide element being provided with spaced abutments, the shield element being provided with an aperture immediately above and aligned with said abutments through which an actuating instrument such as a key may be inserted for access to said abutments of the slide element for slide element actuation, said aperture being of reduced size to preclude digital actuation of the slide element by access through said aperture, and being of a length greater than the distance between said abutments, the slide element selectively engaging the plunger head when the plunger head is disposed in one limit of its range of movement to preclude direct actuation to the other limit.

5. In a device for selectively precluding actuation of a doortract-conditioning plunger, the device comprised of a plunger head movable within limits through an aperture in a frame element of the door to condition the latch mechanism of the door, a housing guard structure located adjacent the plunger head, the guard structure including a shield element and a socket formation below said shield element, a slide element slidably mounted in said socket formation for movement into and out of the path of plunger head travel, the slide element being located below the shield element and extending underneath the frame element of the door to prevent direct digital actuation of said slide element, the slide element being provided with an aperture partially defined by spaced abutments, the shield element being provided with an aperture immediately above and aligned with the aperture in the slide element through which an actuating instrument such as a key may be inserted for access to said abutments for slide element actuation, the shield element aperture being of reduced size to preclude digital actuation of the slide element by access through said aperture and being of a length greater than the distance between said spaced abutments, the plunger head being provided with a shoulder, the slide element selectively engaging the shoulder when the plunger head is disposed in one limit of its range of movement to preclude direct actuation to the other limit.
